UNITED STATES PATENT OFFICE

154,080

DESIGN FOR AN AUTOMOBILE

Clifford Brooks Stevens, Milwaukee, Wis.

Application December 18, 1947, Serial No. 143,209

Term of patent 7 years

(Cl. D14—3)

To all whom it may concern:

Be it known that I, Clifford Brooks Stevens, a citizen of the United States, residing at Milwaukee, in the county of Milwaukee and State of Wisconsin, have invented a new, original, and ornamental Design for Automobile, of which the following is a specification, reference being had to the accompanying drawings, forming part thereof.

Figure 1 is a perspective view of an automobile embodying my new design, said view being taken from the left front corner;

Figure 2 is a front view thereof;

Figure 3 is a right side view of the automobile; and

Figure 4 is a perspective view taken from the right rear corner.

I claim:

The ornamental design for an automobile, as shown.

CLIFFORD BROOKS STEVENS.
